YARN CONE PRINTING DEVICE

George G. Glenn and John D. Glenn, Gastonia, N. C.

Application March 25, 1936, Serial No. 70,870

10 Claims.

(CL 101—35)

Our invention relates to improvements in devices for printing on the interior of yarn cones, and it consists in the combinations, constructions and arrangements herein described and claimed.

5 In the cotton spinning industry the yarn is wound on cones made of stiff cardboard and the material wound is shipped to buyers. It is necessary to identify the various yarns on different cones and this is generally done at present by the use of printed gummed labels.

Furthermore, cones of several colors are often used at the same time in a mill, each color distinguishing a particular number of yarn from others being run. The use of a single color of a cone can of course convey only the difference of a single character, but it is desirable to indicate other qualities or characteristics such as the type of twist, percentages in mixed fibers, the operator's number, etc.

20 Gummed labels deteriorate rapidly. They stick together. The label has to be torn from a perforated sheet, strip or roll; it has to be moistened, placed into the cone and pressed firmly to the inner surface. Furthermore, to give the various kinds of data necessary requires the maintenance 25 of an assortment of printed labels, which is expensive.

An object of the present invention is to provide a device for printing on the interior of the cones, thus dispensing with the use of labels.

30 A further object is to provide a device which will obviate the use of colored cones, thus permitting the cheaper uncolored cone to be used.

A further object of the invention is to provide 35 a simple, practical and durable hand machine by means of which a plurality of indicating characteristics can be printed simultaneously on the inside of the cone.

A further object is to provide a printing device 40 making use of ink and having an inking pad of large capacity from which a large number of impressions can be made.

A further object is to provide a printing device 45 in which there are removable and replaceable lines of type, disposed so as to print in lines coinciding with the geometrical elements of the cone, that is to say, in lines running from the base to the apex of the cone, as distinguished from lines at right angles, the latter being necessarily curved.

50 Other objects and advantages will appear in the following specification and the novel features of the invention will be particularly pointed out in the appended claims.

Our invention is illustrated in the accompanying drawing forming part of this application, in which:

Figure 1 is a sectional view through a cone and through a portion of the printing mechanism.

Figure 2 is an enlarged section through the printing device.

Figure 3 is a section along the line 3—3 of Figure 2.

Figure 4 is a section along the line 4—4 of Fig. 10, 2, and.

Figure 5 is a section along the line 5—5 of Fig. 2.

In carrying out our invention we provide a 15 handle 6 of the shape shown in Fig. 1. The handle is firmly secured by means of a ferrule 7 and pin 8 to a shaft 9, a washer 10, of any suitable resilient material such as felt being disposed adjacent to the ferrule.

The shaft 9 is slidably disposed in a bore 11 of a bell-shaped ink pad holder 12. The latter is preferably a metal casting such as aluminum, and it is provided on the interior with inking pads such as those shown at 13, 14, 15 and 16 in Fig. 4. It will be observed that these inking pads are spaced from one another by partitions 17. The purpose of this plurality of pads is to provide ink of different colors where it is desired. A fewer or greater number of pads might be used without departing from the invention.

30 Secured to the inner portion of the ink pad holder 12 are detachable screws 18, 19 and 20 respectively, see Fig. 4. A plate 21 is loosely held by the heads of the screws. This plate has a tongue 22 which enters a groove in the shaft 9 so as to revolve with the shaft and at the same time to permit the longitudinal movement of the shaft with respect to the plate. The screw 18 is merely a holding screw while the screws 19 and 20 as shown, limit the turning movement 35 of the plate 21 and hence of the shaft 9 to a quarter of a turn.

As will be seen from Fig. 2 the shaft 9 is provided with longitudinal slots 23, in which are pivotally mounted links 24. These links pass 45 through registering slots 25 in a sleeve 26, which has a head 27 at one end, and which is rigidly secured to a base portion 28 at the other. The shaft 9 enters the sleeve as shown in Fig. 2 and terminates at 29. A spiral spring 30 bears on 50 the end of the shaft 9 at one end and on a portion of the base 28 at the other end, a stop member 31 carried by the base limiting the movement of the shaft.

The base has an extension which may be in- 55

tegral therewith, or of a different metal. This extension is shown at 32. It has slots 33 for the reception of type bars 34 which are pivoted at 35, as shown in Fig. 2.

As will be seen from Fig. 1, we have illustrated four of these type bars disposed at ninety degrees apart. They are all alike and the description of one will suffice for all. The upper ends of the type bars are expanded and are slotted to receive the links 24. The latter are pivoted to the individual type bars at 36. Each type bar has secured to it a U-shaped clip 37 by means of screws 37a. The outer ends of these U-shaped clips are bent inwardly toward one another, as shown in Fig. 5. The type blocks, i. e. the lines of type 38, are provided with grooves on their sides arranged to receive the bent end portions of the clips, whereby the line of type is held. The type bars 34 are guided in their movements, as will be explained later, by a circular guide member 39 which is provided with slots 40 for receiving the lower portion of the type bar.

From the foregoing description of the various parts of the device the operation thereof may be readily understood. The type may form any suitable legends to indicate the mill making the yarn, the operator's number, the type of twist, percentages in mixed fibers, etc. as indicated at 41 in Fig. 1.

It may be desirable to have certain indicia in one color and other indicia in other colors, and this is the purpose of the plate 21. Let us assume that the four colors used are black, green, red and blue. In order that the particular line of type may be inked on a particular pad this plate 21 is used. In inking the type the base 28 is placed on a resistant surface, which in practice may be the hand, the bell-shaped ink pad holder is moved downwardly until the washer 42 engages the plate 21, when the type will be in registration with the pads. Now with a downward movement of the plunger the links 24 will cause the type bars to swing outwardly against the pads, thus inking the type. The device is now placed in a cone, that is to say, the base is thrust into a cone, the bell-shaped member 12 is brought down on to the top of the cone and the handle is given a sudden movement downwardly. The base will be frictionally held by the cone and the downward movement of the handle will throw the type out into printing contact with the interior of the cone, as shown in dotted lines, in Fig. 2. The device may be then lifted from the cone after the printing has been done.

It will be noted that the shaft 9 can be given a quarter of a turn. This permits the particular pad to be engaged by the type from one end to the other, but it prevents the engagement of type which are to be inked red, for instance, to engage a pad with green. If it is desired to change the color, as for instance from red to green, then the screws are removed, the disk or plate 21 is revolved to the position desired and the screws are again reinserted to hold the plate in a position to permit a quarter of a revolution, but no more.

We have shown the device as having four lines of type and four pads, but obviously there might be more or less without departing from the spirit of the invention.

The large capacity of the inking pads obviates the necessity of reinking for a long period. The cones are very quickly printed, since one thrust is all that is necessary as distinguished from the trouble in applying labels. As a consequence

there is a great saving in the time of printing the data, as well as in the cost.

We claim:

1. In a printing device for yarn cones, a base portion for frictionally engaging the interior of the cone, a shaft movable toward said base portion, movable type, and means actuated by the movement of the shaft toward the base for forcing the type into printing engagement with the interior wall of the cone. 5

2. In a printing device for yarn cones, a base portion for frictionally engaging the interior of the cone, a shaft movable toward said base portion, a type bar pivotally mounted on said base portion, and bearing type, and means actuated by the movement of the shaft toward the base for swinging the type bar on its pivot to bring the type into printing engagement with the interior wall of the cone. 10

3. In a printing device for yarn cones, a base portion for frictionally engaging the interior of the cone, a shaft movable toward said base portion, a plurality of type bars pivotally mounted on said base, and a link connecting each type bar with the shaft whereby the movement of the shaft toward the base will swing the type bars outwardly to bring the type into printing engagement with the interior wall of the cone at points spaced apart thereon. 15

4. In a printing device for yarn cones, a base portion for frictionally engaging the interior of the cone, a shaft movable toward and away from said base portion, a bell-shaped ink pad holder having a central bore to receive the shaft and being movable longitudinally of the shaft, a plurality of type bearing bars pivotally connected to said base and being receivable within the bell-shaped ink pad holder, and links connecting the shaft with the type bearing bars for swinging the bars outwardly to bring the type against the ink pads when the shaft is moved toward the base and to swing them inwardly toward the shaft when the shaft is moved away from the base. 20

5. In a printing device for yarn cones, a base portion for frictionally engaging the interior of the cone, a central sleeve secured to the base, type bearing bars pivotally connected to the base at one end and arranged to engage the sleeve in inoperative position, a shaft having an end arranged to enter the sleeve, a spring for normally holding the shaft away from the sleeve and links connected with the shaft and with the type bars for swinging the type bars outwardly away from the sleeve when the shaft is moved toward the base. 25

6. In a printing device for yarn cones, a base portion for frictionally engaging the interior of the cone, a central sleeve secured to the base, type bearing bars pivotally connected to the base at one end and arranged to engage the sleeve in inoperative position, a shaft having an end arranged to enter the sleeve, a spring for normally holding the shaft away from the sleeve, links connected with the shaft and with the type bars for swinging the type bars outwardly away from the sleeve when the shaft is moved toward the base, a bell-shaped ink pad holder having a central bore to receive the shaft and being movable longitudinally of the shaft to a position to surround the type of the type bearing bars, and an ink pad disposed around the inner wall of the ink pad holder for inking the type. 30

7. A printing device for yarn cones, a base portion for frictionally engaging the interior of the cone, a shaft movable toward said base portion, a type bar pivotally mounted on said base 35

- portion and bearing type, a bell-shaped ink pad holder having a central bore arranged to receive the shaft and slideable to bring the type within the holder, an ink pad disposed on the interior wall of the holder, and means actuated by the movement of the shaft toward the base for swinging the type bar on its pivot to bring the type into contact with the pad when the ink pad holder is in one position, and to bring the type into printing engagement with the interior wall of the cone when the base portion engages the interior of the cone and the ink pad holder is in a shifted position.
8. In a printing device for yarn cones, a shaft having a longitudinal slot, a bell-shaped ink pad holder having a central bore arranged to receive the shaft and being longitudinally movable thereon, a guide plate having a bar to receive the shaft and having a tongue arranged to enter the slot, means for rotatively securing the plate to the ink pad holder, and for limiting the rotative movement of the plate with the shaft, and a plurality of ink pads disposed on the interior wall of the ink pad holder.
9. In a printing device for yarn cones, a base portion, a shaft movable toward said base portion, a plurality of type bars pivotally mounted on said base bars and bearing type, a bell-shaped ink pad holder having a central bar to receive the shaft and being movable longitudinally of the

shaft to a position to surround the type bars, a plurality of ink pads disposed on the interior wall of the ink pad holder, said pads containing inks of different colors, means actuated by the movement of the shaft toward the base for swinging the type bars on their pivots to bring the type into inking engagement with the pads, and means for confining the engagement of the type on each bar to a pad bearing ink of a predetermined color.

10. In a printing device for yarn cones, a base portion, a shaft movable toward said base portion, a plurality of type bars pivotally mounted on said base bars and bearing type, a bell-shaped ink pad holder having a central bar to receive the shaft and being movable longitudinally of the shaft to a position to surround the type bars, a plurality of ink pads disposed on the interior wall of the ink pad holder, said pads containing inks of different colors, means actuated by the movement of the shaft toward the base for swinging the type bars on their pivots to bring the type into inking engagement with the pads, and means for confining the engagement of the type on each bar to a pad bearing ink of a predetermined color.
